DESIGN FOR A KNITTED HAND-COVERING

Alexander J. Friedlander, Milwaukee, Wis., assignor to M. Friedlander Knitting Company, Milwaukee, Wis., a corporation of Wisconsin

Application January 19, 1935, Serial No. 54,927

Term of patent 7 years

To all whom it may concern:

Be it known that I, Alexander J. Friedlander, a citizen of the United States, residing at Milwaukee, in the county of Milwaukee and State of Wisconsin, have invented a new, original, and ornamental Design for a Knitted Hand-Covering, of which the following is a specification, reference being had to the accompanying drawing, forming part thereof.

In the drawing, the single figure is a plan view of a knitted hand-covering embodying my new design.

The important features of the present design,

comprising the fashion knitted cuff and pendant ornamentation extending centrally away from the cuff and along the back of the hand-covering, are shown in solid lines, and the immaterial features are illustrated in dotted lines. While the fashion knitted cuff is continuous, the palm side of the hand-covering is devoid of ornamentation such as is applied to the back.

I claim:

The ornamental design for a knitted hand-covering, substantially as shown and described.

ALEXANDER J. FRIEDLANDER.
